ARRANGEMENT FOR THE ONE SIDED BAND MODULATION OF HIGH FREQUENCY VIBRATIONS

Application filed February 2, 1926, Serial No. 85,460, and in Germany February 3, 1925.

It is common knowledge that in the modulation of high frequency oscillations as a rule the amplitude is varied in a low frequency rhythm so that the average value of the high frequency amplitude fluctuates in accordance with the low frequency. It is further known that, in this kind of modulation, an exact and true transmission of the low frequency amplitude is not obtained as can be easily seen from the mathematical definition of the proceeding. If the high frequency is designated by N , the low frequency by n , the time by t , the high frequency amplitude by A , the low frequency amplitude by a , and the initial amplitude designated by the index o , a modulated oscillation has the equation:

$$A = A_0 \sin Nt + A_0 a_0 \sin Nt \sin n t \quad I$$

This equation may be transformed into

$$A = A_0 \sin Nt + \frac{A_0 a_0}{2} \cos (N-n)t + \frac{A_0 a_0}{2} \cos (N+n)t \quad II$$

The modulated high frequency wave is composed of three frequencies, viz., the original high frequency and the sum and the difference from high- and low frequency.

The modulation may also be explained by interference, the frequency $N+n$ as well as the frequency $N-n$ executing with the frequency N a beat note of frequency n . The two beat notes assist one another in their mutual effect. The Equation II shows however that, besides these two interferences which have just been mentioned, the two side waves $N+n$ and $N-n$ do also interfere, the beat frequency of the same being equal to $(N+n) - (N-n) = 2n$, i. e., double the original low frequency. At the receiving station the modulation amplitude, at the surging frequency is rendered audible and is observed as sound. With the above described kind of modulation one hears therefore in the receiver besides the original low frequency amplitude the octave of the same. The received sounds are therefore distorted. This distortion is especially disturbing if

the transmission amplitude is very strongly modulated. The degree of modulation is therefore maintained very low in accordance with the present state of the art of wireless telephony in order to maintain within moderate limits the sound distortion owing to the prominence of the octaves. The transmitter therefore normally operates at a relatively low degree of efficiency.

Methods have become known to suppress one of the two side bands. It is difficult to eliminate a side-band by the usual resonance tuning method, since the breadth of frequency band obtained by modulation expressed as percentage in respect to the carrier frequency is much narrower than the technically obtainable minimum width of a resonance curve. This specially holds for short waves. Even if a sufficiently sharp resonance curve can be obtained, for instance with comparatively longer waves, an unequal influence on the several portions of the frequency band, i. e., distortion of the speech currents will be unavoidable. Filters with comparatively steep ascent are then employed.

According to this invention the suppression of one side band is effected by means of a compensation arrangement which is shown by way of example in the accompanying drawing.

Fig. 1 is a diagrammatic representation of one embodiment of my invention for eliminating one side band and

Fig. 2 is a diagrammatic representation of another embodiment of my invention where in both the carrier wave and one side band are eliminated. The oscillations produced by a high frequency generator 1 of any convenient type are divided in such a manner, e. g., by properly adjusting the coupling conditions, that on the grids of the valves 2 and 3 similar voltage amplitudes exist. The high frequency grid amplitudes in the valve 3 are displaced 90° in phase with regard to those on the valve 2 by means well known in the art, this being attained in Fig. 1 by the aid of the adjustable condenser 4. The low frequency amplitudes coming from the leading in wire 5 are conducted to the

valves 2 and 3 at voltages which are also equal to each other, the low frequency amplitude in the grid of the valve 3 being also displaced 90° in phase with regard to that on the grid of valve 2. In Fig. 1 this is indicated by the connection of a voltage transformer 6 with valve 2 and voltage transformer 7 with valve 3. By properly choosing the coupling factors of the transformers the voltage drop on the comparatively low resistance of the secondary winding of 7 can be displaced 180° in phase with regard to the inducing current of the circuit 5, while the voltage impressed across the secondary winding of 6 is displaced 90° in phase with regard to the current in circuit 5 as is well known in the art. The anode currents of the valves 2 and 3 are added and transferred upon the output circuit, for instance the antenna 8. Instead of the ordinary grid modulation shown by way of example in Fig. 1 any other kind of modulation might be used and high- and low frequency amplifiers may be used in controlling the amplitude of the signaling current.

To explain the operation it may be supposed that the modulation proceeding represented in the above stated Equation II takes place in the valve 2. The proceeding in the valve 3 is then explained by the following equation:

$$A' = A_0 \cos Nt + A_0 a_0 \cos Nt \cos nt \quad \text{III}$$

which may be transformed into:

$$A' = A_0 \cos Nt + \frac{A_0 a_0}{2} \cos (N-n)t + \frac{A_0 a_0}{2} \cos (N+n)t \quad \text{IV}$$

By addition of Equations II and IV the oscillation amplitude supplied to the work circuit, for instance to the antenna becomes:

$$A'' = A_0 (\sin Nt + \cos Nt) + A_0 a_0 \cos (N-n)t \quad \text{V}$$

If the oscillation amplitudes in the anode circuits of the valves 2 and 3 were not added as of the same phase but of opposite phase the Equation IV would have to be subtracted from II. In this case the frequency N and the sum $N + n$ are obtained. In both cases one of the two side frequencies or side bands has disappeared and by similar phase or opposite phase combination of the modulation proceedings only the one or the other side band may be supplied to a work circuit.

Methods are known for modulating a high frequency carrier wave in such a manner that the carrier wave itself does not occur in the work circuit but only the two side bands are present. Combining such a method with the method underlying this invention, the high frequency oscillation as well as the low frequency oscillation being displaced 90° in

phase in one circuit with regard to the other, only one side band will be obtained in the work circuit in an analogous manner, without the carrier wave. In Fig. 2 such a method is diagrammatically illustrated by way of example, the well-known push-pull modulation being supposed to be used for the suppression of the carrier wave. 1 is the high frequency generator, 2_a and 2_b are the one pair of valves for the push-pull modulation, 3_a and 3_b are the other pair of valves for the push-pull modulation, a phase displacement of 90° between the high frequency grid amplitudes of the two valves with the aid of the condenser 4 being presumed. The low frequency transformer 6 serves for the modulation in the group of valves 2_a , 2_b from the circuit 5, and the transformer 7 serves for the modulation of the group of valves 3_a , 3_b at phase displacement of 90° with regard to 2_a , 2_b . The modulations in 2_a , 2_b and 3_a , 3_b , free from the carrier waves, are added by common coupling at the same phase or at opposite phases in a work circuit, for instance the antenna 8.

I claim:—

1. A system of modulating carrier frequency with suppression of carrier wave and one of the side-bands comprising electron device arrangements, each one connected to suppress the carrier wave, separate input circuits for said arrangements, a common output circuit for said arrangements, means for shifting the phase by 90° at carrier frequency on one of said arrangements, and means for shifting the phase by 90° at modulating frequency on one of said arrangements.

2. The method of producing a single side band carrier suppressed modulated wave which consists in dividing a modulating wave into two components producing a 90° phase shift between said components, dividing a carrier frequency wave into two components equally having a 90° phase difference therebetween, utilizing one component of said carrier wave and one component of said modulating wave to produce side bands of modulated frequencies, utilizing the remaining component of said carrier frequency wave and the remaining component of said modulating wave to produce further side bands of modulated frequencies, superimposing resultant pairs of side bands to eliminate all but a single side band carrier modulated wave and at the same time suppress the carrier.

3. A system for producing a single side band carrier suppressed modulated wave which comprises in combination a source of modulating waves, two circuits branched therefrom, means in said branched circuits for producing a phase shift in the respective branch circuits, a source of carrier frequency, means for deriving from said source two carrier wave components, means for produc-

- ing a phase shift between said carrier wave components, means for modulating said derived carrier waves by the output wave from said branch circuits respectively to produce
 5 upper and lower side bands of each of said derived carrier waves, means for superimposing the resultant pairs of side bands whereby both the carrier and all but a single side band are balanced and suppressed.
- 10 4. A system for producing a single side band carrier suppressed modulated wave which comprises in combination a source of modulating waves, two circuits branched therefrom, means in said branched circuits
 15 for producing a phase shift in the respective branch circuits, a source of carrier frequency, means for deriving from said source two carrier wave components differing from each other in phase by 90° , means including a push-pull circuit arrangement for modulating said derived carrier waves by the output wave from said circuits respectively to produce carrier suppressed upper and lower side bands of each of said derived carrier waves,
 20 means for superimposing the resultant pairs of side bands whereby one side band of each pair is balanced out and the remaining side bands are added.
 25 5. A system of modulating a carrier wave with suppression of the carrier frequency and one of the side bands comprising a pair of electron tube arrangements, each of said arrangements being connected to suppress the carrier frequency, separate input circuits
 30 for said arrangements, a common output circuit for said arrangements, means for producing separate carrier frequency components and separate modulating frequency components, respectively, to be applied to
 35 said arrangements respectively, and means for shifting the phase of one of said carrier frequency components and one of said modulating frequency components by 90° with regard to the remaining carrier frequency component and the remaining modulating frequency component respectively.
 40 6. In a modulating system as described in claim 5 in which each of said arrangements comprises two vacuum tubes with their grid controlled in push-pull fashion by the respective carrier frequency component.
 45 7. A system of modulating carrier frequency with suppression of the carrier wave and one of the side bands comprising two electron device arrangements including push-pull circuit connections to suppress the carrier wave; separate input circuits for said arrangements; a common output circuit for
 50 said arrangements; means for applying carrier currents of equal frequency to said arrangements; further means for shifting the phase 90° at carrier frequency on one of said arrangements; and means for modulating both carrier currents in said arrangements in
 55 accordance with a common modulating cur-
